BENOIT ROUX, OF CINCINNATI, OHIO, ASSIGNOR TO M. GREENWOOD & CO.,
OF SAME PLACE.

Design No. 3,844, dated February 8, 1870.

DESIGN FOR A PAIR OF GATE-HINGES.

The Schedule referred to in these Letters Patent and making part of the same

I, BENOIT ROUX, of Cincinnati, in the county of Hamilton, and State of Ohio, have invented a new Design for a Pair of Gate-Hinges; and I hereby declare that the said invention is correctly represented in the accompanying drawing, which forms part of this specification, and in which—

Figure 1 represents an upper, and
Figure 2, a lower hinge.
I claim, as my invention—

The design for a pair of gate-hinges, substantially as herein represented.

In testimony of which invention, I hereunto set my hand.

BENOIT ROUX.
